INSULATOR SUPPORTING PIN

Frederick P. Sexton, Lachine, Quebec, Canada

Application October 1, 1934, Serial No. 746,315

3 Claims. (Cl. 173—321)

In order to realize the full mechanical strength of a porcelain insulator and to prevent difficulties due to radio interference, it is necessary to screw the insulator home until the top of the 5 pin hole is brought in contact with the upper end of the lead head or mantle of the supporting pin. With the pins now in use this is often impossible owing to irregularities in the pin hole due to shrinkage and distortion of the porcelain 10 during the firing process. In such instances the gap left between the pin and the top of the pin hole not only results in loss of mechanical strength but also gives rise to radio interference. It also frequently happens that the top groove 15 of the insulator is not properly lined up when the insulator is screwed home. To correct this condition the insulator must be backed off or else the pin must be moved in the cross arm to which it is attached. Owing to the taper of 20 the pin hole and the engaging threaded portion of the pin it is not desirable to back off the insulator after it is once screwed home, since this loosens the insulator and also leaves an undesirable gap between the top of the pin hole 25 and the top of the pin. The movement of the pin in the cross arm to line up the insulator groove is also objectionable on account of the trouble involved.

The present invention provides a pin designed 30 to overcome the above mentioned difficulties and to ensure perfect seating of the insulator thereon regardless of whether the pin hole in the insulator is true or has been distorted by shrinkage during the firing process. An important feature 35 of the invention consists in the provision of soft metal projections at the upper end of the pin adapted to be engaged by the top of the pin hole when the insulator is screwed home. These projections ensure a proper ground connection 40 between the pin and the top of the insulator while providing sufficient clearance for expansion purposes. Being made of soft metal capable 45 of flowing under pressure they also enable the top groove of the insulator to be properly lined up without backing off the insulator or resorting to the troublesome practice of moving the pin in the cross arm. In this connection it may be explained that, while the insulator may be considered to be screwed home as soon as the top 50 wall of the pin hole contacts the tips of the projections, the latter will flow, under pressure, to permit such slight further screwing on of the insulator as may be necessary to line up the insulator groove. Another feature consists in providing 55 the pin with a starting thread located below

said projections immediately in advance of a non-threaded soft metal portion in which the insulator cuts its own thread as it is screwed home. This ensures perfect seating of the insulator regardless of whether the pin hole is true 5 or distorted. A still further feature, which is optional, consists in providing the pin with a further threaded portion adapted to be engaged by the internal thread of the insulator after the latter has cut its way through the soft metal 10 portion adjoining the starting thread.

The foregoing and other features and advantages of the invention will be more readily understood from the following detailed description taken in connection with the accompanying 15 drawing, in which—

Fig. 1 is a vertical sectional view through an insulator mounted on a pin constructed in accordance with a preferred embodiment of the present invention. 20

Fig. 2 is a top plan view of the insulator supporting pin.

Fig. 3 is a view, in side elevation, of the insulator supporting pin.

Fig. 4 is a view similar to Fig. 3 but showing 25 a slight modification.

In the construction shown in Figs. 1 to 3 inclusive, 5 designates a conventional insulator pin having a lead mantle 6 cast on or otherwise secured to its upper end. The mantle has a 30 slight inward taper towards its upper end on which are formed four vertical projections 5a which, in the form shown, taper to a point at their upper ends. The mantle is also cast or otherwise provided with upper and lower threaded portions 7 and 8 separated by a non-threaded intermediate portion shaped to present a series of laterally spaced lengthwise extending ribs 9. These ribs are arranged so that the insulator 10 cuts its own thread therein as it is screwed home 40 against the projections 5a following initial engagement of the insulator thread 11 with the starting thread 7. In the case of relatively long insulators, such as that shown in Fig. 1, the insulator thread 11 is preferably engaged with the 45 bottom thread 8 of the mantle after cutting its way through the ribs 9. However, the threaded portion 8 at the lower end of the mantle is not absolutely essential and may be dispensed with as shown in Fig. 4, in which the ribs 9 extend 50 from the starting thread 7 to the lower end of the mantle. When relatively short insulators are used with a pin of the type shown in Fig. 4, the ribs 9 may be made shorter so that their lower ends terminate any desired distance above 55

the lower end of the mantle. As soon as the insulator is screwed home to the point where the top of the pin hole bears against the tips of the projections 5a, a satisfactory ground connection is established between the pin and the top of the insulator. At the same time, a perfect seating of the insulator on the pin is obtained due to the fact that the threads cut in the ribs 9 conform exactly to the insulator thread. In order to properly line up the insulator groove a slight further screwing on of the insulator may be necessary after the top wall of the pin hole is engaged with the tips of the projections 5a. This, however, is easily accomplished owing to the fact that the said projections are made of soft metal capable of flowing under pressure and, hence, may be compressed between the top portions of the mantle and the pin hole, as shown in Fig. 1. In some insulators the top portion 15 of the pin hole is made dome-shaped and, with this in view, the outer sides of the projections 5a are curved longitudinally so that they will be crowded inwardly as they are compressed between the insulator and the dome-shaped upper portion of the pin hole. The spacing of the projections 5a is important in that, even when the projections are compressed as shown in Fig. 1, sufficient space is left therebetween for expansion purposes.

Having thus described what I now conceive to be the preferred embodiments of my invention, it will be understood that various modifications may be resorted to within the scope and spirit of the appended claims and that the various features of improvement may be used singly as well as in combination. For example, the addition of the soft metal top projections 5a to the externally threaded lead head of an otherwise conventional supporting pin would ensure a proper ground connection between the pin and

the top of the insulator in addition to its advantages with respect to lining up the insulator groove. Likewise, the shaping of the lead head or mantle of an insulator supporting pin to provide a starting groove in advance of a non-threaded soft metal portion in which the insulator cuts its own thread would be an improvement even in the absence of the projections 5a.

Having thus described my invention, what I claim is:

1. An insulator supporting pin provided with a mantle of soft metal shaped to present a starting thread above one or more non-threaded axially extending ribs of soft metal in which a continuation of the lower end of the starting thread is cut by the insulator thread as the insulator is screwed home after being initially engaged with the starting thread. 10
2. An insulator supporting pin provided with a mantle of soft metal shaped to present upper and lower threaded portions including a series of laterally spaced axially extending ribs in which the insulator cuts its own thread as it is screwed home after being initially engaged with said upper threaded portion. 20
3. An insulator supporting pin provided with a mantle of soft metal covering the top and upper side surfaces of the pin, said mantle having a starting thread formed therein in advance of a non-threaded soft metal portion in which a continuation of the starting thread is cut by the insulator as it is screwed home, and a plurality of projections formed integral with the top portion of said mantle and projecting upwardly therefrom, each of said projections tapering to a point and being spaced a substantial distance from each of the remaining projections. 25 30 35
